VENTILATING APPARATUS

Vernon P. Winton, Memphis, Tenn.

Application August 11, 1937, Serial No. 153,595

7 Claims. (Cl. 98—43)

The invention relates to a ventilating apparatus designed particularly and primarily for use in dwelling houses, especially those in rather warm climates, though its use is not so restricted, 5 inasmuch as it is capable of employment in factories, warehouses or anywhere else where forced ventilation is desired or necessary.

Speaking more specifically, the invention has to do with the problem of ventilating, and therefore 10 keeping uniform the temperature in, or of, dwelling houses located particularly in the southern ones of the United States where conditions are such that the air temperature is, at night, fairly reasonable or moderate but rises to a great 15 ly excessive degree in daytime.

The point involved in this is that during the evening and at night the temperature is comparatively low and therefore what is commonly considered to be livable, whereas in the daytime 20 the temperature is excessively high. If, then, a means can be devised to introduce within the dwelling house, or other building, night air at its comparatively moderate temperature and restrict the substitution or adulteration of such comparatively cool air by the sunshine-heated air of daytime, the problem is solved to a practically major 25 extent, it being well known that if cool, night air is admitted to a dwelling or other enclosure and the doors and windows thereof subsequently closed, the temperature will normally be reasonably 30 comfortable during the ensuing day.

It is also well known that numerous refrigeration systems have been devised by means of which chilling of the atmosphere is obtained or 35 attained. The disadvantages associated with such systems are that the temperature may be excessively low as is evidenced by the discomfort when the average person enters a so-called "air-conditioned" store or the like, coupled with the 40 extraordinary expense involved in the installation of the necessary apparatus.

It is with the above facts in view that I have devised the present invention which has for its general and primary object the provision of a 45 simply constructed and operated device designed to be installed in the attic or air space beneath the roof of a dwelling house or other building for the purpose of sucking in outside air continuously if desired though preferably at night 50 and expelling it through the windows of the attic or any air vents which might be provided in case of installation in a warehouse, factory or plant of any kind.

In the southern States of this country it is 55 known that the night air is comparatively cool

and that if it can be imprisoned or confined within a house until the next day the house will be reasonably comfortable. It is, therefore, an important object of the invention to provide means whereby a householder will be enabled, at any 5 or all times, but particularly at night, to exhaust the heated atmosphere from his dwelling or other place and replace it with a constant supply of fresh air drawn in from outdoors when the temperature is naturally lower, it being a 10 feature of the invention that the doors and windows of the building may be subsequently closed, at least for the ensuing day, so that undesired heated air will be excluded.

A more specific object of the invention is to provide a ventilating apparatus embodying a motor driven fan adapted to be mounted, for example, in the floor of the attic and involving the employment of means whereby heated air may be sucked up directly and vertically from the entire interior 20 of the house and discharged through whatever vents or windows are present.

It is not new, broadly speaking, to install some sort of a ventilating fan or apparatus in an attic, or its equivalent, and some of such devices embody more or less lengthy wind-tunnels with their attributes of cumbersomeness and expense, such installations additionally being difficult where there is a very limited air space, perhaps from 25 two to four feet between the attic floor and the roof, such a space being practically insufficient to accommodate the conventional type of ventilator involving a vertical fan, that is to say one in which the axis of rotation is horizontal, together 30 with the adjunctive elements of a conduit of 35 some sort or other.

As a preliminary summary it may be said that the present invention consists really in providing a unitary and portable structure which may be manufactured and assembled at some convenient 40 plant and installed, without the exercise of any particular degree of skill and experience, within a home, or other place, at an opening in the ceiling of the upper story or, in other words, immediately above an opening in the attic floor, for 45 the purpose of extracting the vitiated and heated air and discharging it through any and all windows or other openings which may exist.

An important object of the invention is to provide a ventilating apparatus in which the necessary fan is mounted for rotation about a vertical axis and is so constructed as to discharge the 50 sucked up air horizontally or laterally outwardly toward all vents, windows or the like, the blades 55

of the fan being peculiarly and especially constructed to accomplish this result.

Another very important object of the invention is to provide a construction wherein adequate, and in fact most efficient, provision is made for changing the speed of rotation of the fan itself without changing the speed of rotation of the driving motor, said speed change means being manually operable and controllable, depending upon the necessities or exigencies of service.

A more specific object of the invention is to provide a ventilating apparatus embodying a rotary font having its shaft equipped with a single driven pulley engaged by a belt driven by a multi-pulleyed motor, the position of which may be manually varied to change the relationship of its pulleys to the pulley on the shaft of the fan to bring about the different desired selective speeds.

An additional object of the invention is to provide an apparatus or device of this character which will be simple and inexpensive to manufacture, easy to install, positive in operation, efficient and durable in service, and a general improvement in the art.

To the attainment of the foregoing and other objects and advantages the invention preferably consists in the details of construction and the arrangement and combination of parts to be hereinafter more fully described and claimed and illustrated in the accompanying drawings in which:

Figure 1 is a plan view of the device with portions broken away for the sake of clearness.

Figure 2 is a vertical longitudinal cross sectional view taken on substantially the line 2-2 of Figure 1.

Figure 3 is a fragmentary detail horizontal sectional view through the mechanism permitting the change in the speed of rotation of the fan as compared with that of the motor, this view being taken on substantially the line 3-3 of Figure 2.

Figure 4 is a detail side elevation with parts broken away and in section showing the driving means.

Figure 5 is a detail cross section taken on the line 5-5 of Figure 1.

Referring more particularly to the drawings, I have shown the device as comprising a base frame 10 which is represented as of rectangular form, although it need not be, and which may be constructed of wood or metal. This frame is intended to be mounted above an opening 11 in the floor of an attic, that is to say in the ceiling 55 of the room or hallway beneath. Logically the latter is the better location inasmuch as all the rooms in the house necessarily communicate with a hallway of some sort regardless of how small it may be. Located above the opening is a grille 60 or lattice structure 12.

Rising from opposite sides of the frame 10 are pairs of supporting members 13 which may be mounted in any one of several different ways although in the present instance these members 65 are shown as pipes or other tubes having their lower ends engaged upon dowel pins 14 or the like appropriately secured to the upper edges of the frame 10, possibly by the simple expedient of being located within recesses 15 bored therein. There are so many mechanical equivalents possible which are of such an obvious nature that it is deemed unnecessary to enumerate them. The upper ends of the pipes 13 are telescopically 70 engaged within socket members 16 which in turn support a pair of angle bars 17 upon which is

secured, as by bolts 18, the horizontal outstanding flange 19 of a ring 20 which is T-shaped in cross section or which in other words includes, in addition to the horizontal flange 19, a vertical flange 21.

The space between the main or base frame 10 and the ring 20 is intended to be enclosed and to effect this I provide a flexible housing 22, preferably of fabric, which has its lower end portion located within the confines of the frame 10 and secured thereto as by strips 23 fastened in place in any desired manner. Secured against the outer face of the vertical flange 21 beneath the horizontal flange 19 of the ring 20 is a ring 24 upon which the upper end of the flexible housing 22 is telescopically engaged, any desired means being provided for effecting positive securing.

Appropriately mounted and extending transversely of the ring 20 is a pair of parallel angle bars 25 upon which are bolted the legs 26 of a socket 27 which supports the entire fan assembly to be described. It should be mentioned, in passing, that the horizontal flange 19 of the ring 20 supports an upstanding cylindrical shield or shell 28 which surrounds the above mentioned fan structure.

The fan assembly preferably comprises a hub 29 containing a roller bearing structure 30 engaged upon an upstanding spindle 31 mounted within the socket 27. Projecting radially from the hub 29 and secured with respect thereto by means to be described are arms 32 which carry fan blades 33 which, as clearly disclosed in Figure 5, have their major portions inclined at an angle of approximate thirty degrees and which have their upper edges terminating in horizontal portions or extensions 34, the purpose being that when the fan is rotated air drawn up thereby through the opening 11 and grille 12 and conducted through the flexible housing 22 will be forced laterally outwardly in contradistinction to being discharged in the form of a vertical column as is the case with the ordinary type of fan.

The hub 29 and the radial arms 32 may be considered as a spider and the preferred construction is that the hub be formed with sockets 35 within which are pairs of projections 36 extending toward each other. The arms 32 are cast within the sockets and it is consequently clear that the projections 36 therein will operate as a positive lock to prevent any looseness or detachment of the arms under the influence of centrifugal force, it being remembered that the fan is intended to be driven at a fairly high speed. If the arms 32 were firmly separate elements attached to the hub by rivets, bolts or the like, it is easily conceivable that looseness might develop whereas the present construction wherein actual casting is resorted to will preclude such a contingency.

The fan assembly also includes a single driven pulley 31 of the V type having its hub 38 of hollow form and secured to the hub 29, as by cap screws 39. As the hub has been described as containing the roller bearing structure 30, it is obviously chambered or of hollow form and the lower end of the hollow hub 38 of the driven pulley is shown as telescoped therein, the purpose being to provide a joint which will be very close fitting. Lubrication may be effected by an oil or grease cup 40 preferably of the pressure type and this cup is located centrally of the hub 38 which is made hollow, as above mentioned,

to enable the lubricant to gain access to the roller bearing structure 30, the above mentioned close fit between the hubs 38 and 29 being for the purpose of preventing any leakage and flying 5 about of the lubricant when the fan is in operation, or at any other time for that matter. Leakage of the lubricant at the lower end of the hub 29 is prevented by providing any suitable or preferred oil or grease seal at the bottom of 10 the roller bearing assembly as shown above the step 41 on the spindle 31.

As it is most desirable to avoid any vibration while the fan is in operation the sockets 16 are preferably provided with bushings or sockets 42 15 of rubber immediately surrounding the upper ends of the tubes 13. Within these bushings or sockets, I provide coil springs 43 located above the upper ends of the tubes or pipes 13. Clearly the springs 43 and also the rubber bushings 42, 20 will operate to cushion the angle bars 17 and consequently all the parts carried thereby including the entire fan assembly so that vibration will be reduced to a minimum and objectionable noise prevented. If preferred, in some installations, the springs might conceivably be omitted. 25 The flexible housing 22 is also a sound deadener or absorber in case there is any tendency for the development of noise.

The means for driving the fan consists of an 30 electric motor and a belt drive and embodies a specially constructed mounting for the motor enabling the speed of rotation of the fan to be readily varied without changing the motor speed. The drive mechanism comprises an upstanding bracket 44 which is U-shaped in horizontal cross section or which in other words has parallel sides 35 45. This bracket is shown as mounted on a plurality of screw studs 46 which pass through one of the angle bars 17 and through a plate 47 disposed thereagainst, shoulders 48 being provided on the studs engaging against the outer face of the plate 47. These studs carry nuts 49 bearing against the inner face of the angle bar 17 and also carry pairs of nuts 50 engaging 45 against opposite sides of the bracket 44. By adjusting the nuts 50 the bracket may be moved to a certain extent toward or from the ventilating device or frame thereof. The sides 45 of the bracket are provided at their intermediate 50 portions with outwardly extending ledges 51. Above the ledges the sides 45 are formed with inclined slots 52.

An electric motor 53 is carried by a U-shaped bracket 54 located partly within the confines of 55 the bracket 44 and the bracket 54 is pivotally mounted by virtue of a rod 55 which passes through holes in the sides of the bracket 54 and through the slots 52 in the sides of the bracket 44. Secured upon the rod 55 outwardly of the 60 bracket sides 45 are stop or guide plates 56 adapted to rest upon the ledges 51 and it will be observed that these plates are eccentric with respect to the rod for a purpose to be described. Outwardly of the plates 56 the rod carries handles 57.

The motor shaft carries a plurality of stepped pulleys 58, 59 and 60 of the V-type. The actual driving means for the fan consists of a belt 61 70 trained about the fan pulley 37 and about a selected one of the pulleys 58, 59 and 60 depending upon the desired speed of the fan. Regardless of which pulley is engaged by the belt, the belt is always maintained taut owing to the fact that the motor is pivotally mounted by virtue of 75 the engagement of the bracket 54 upon the rod

55 which enables the weight of the motor to apply tension upon the belt. If necessary, to take up excessive slack in the belt or to loosen it so that the motor will be in a vertical position, the bracket 44 can be moved bodily toward or away from the ventilator structure by adjusting the nuts 50.

Assuming that the device has been constructed and assembled as shown and installed at the desired location within an attic or air space beneath the roof of a house or other building, 10 it will be understood that when the motor 53 is in operation the belt 61 will be driven and will in turn drive the pulley 37 and by virtue of the connection afforded by the studs 39 between the hub of the pulley 37 and the hub 29 of the fan, 15 the fan will be rotated. Owing to the inclination of the fan blades air within the building will be sucked up through the opening 11 and grille 12 into and through the flexible housing or skirt 22 and will pass upwardly within the confines 20 of the shell or shield 28 and be discharged at the top thereof in a horizontal or laterally outwardly direction, the air eventually being forced out through the windows or whatever air vents are provided in the attic or air space beneath 25 the roof. This outward radial deflection of the air results from the provision of the horizontal extensions or flange portions 34 at the upper edges of the fan blades. It will be noted that all the fan mechanism is at the exhaust side of 30 the device and the rotating parts will therefore be automatically cooled on account of the contact of the air current therewith. During the operation of the device any vibration will be absorbed owing to the provision of the rubber bushings or 35 sockets 42 within which the supporting pipes or tubes 13 are engaged together with the springs 43 located above the upper ends of the pipes. As vibration is thus prevented noise will not be developed and in fact any sound occasioned by the 40 operation of the mechanism will be additionally deadened or absorbed owing to the provision of the flexible housing or skirt 22.

The operation of the speed change mechanism is as follows: When the drive belt 61 is engaged 45 about the largest or lowermost motor pulley 58, as shown in Figure 2, the motor is in its most elevated position which is maintained by engagement of the guide plate edges most remote from the rod 55 upon the ledges 51. When the motor 50 is in this position and the belt engaged about the pulley 58 it is of course clear that the fan is rotated at its maximum speed. Assuming that it is desired to reduce the speed to the minimum, the operator grasps the handles 57 and turns 55 them in either direction one-half turn or through an angle of one hundred and eighty degrees, thereby inverting the guide plates 56 until the edges thereof closest to the rod 55 will engage upon the ledges 51. The corners of the guide 60 plates are rounded off as shown so as to facilitate this and the action is still further facilitated if the operator pull upwardly upon the handles 57 so as to support the weight of the motor while the guide plates are being inverted. When the 65 guide plates are moved into this second mentioned position, as shown in Figure 4, the rod 55 will slide downwardly along the slots 52, thereby increasing the distance between the motor shaft and the axis of the fan. The belt 61 is of course 70 manually shifted from the pulley 58 onto the smallest pulley 60. The purpose in inverting the guide or stop plates 56 is twofold, one being to lower the motor so that the smallest pulley 60 will be in alignment with the fan pulley 37, and the 75

other being to move the motor away from the fan to compensate for the difference between the diameters of the pulleys 58 and 60, thereby maintaining the belt taut as well as in proper alignment.

If the intermediate speed is desired, the belt is engaged about the central pulley 59 and the handles 57 are manipulated to rotate the guide plates one-fourth turn in either direction so as to bring either of the other edges thereof into engagement with the ledges 51. In this instance the motor will be lowered and also moved outwardly away from the fan to a less degree than is the case when shifting the belt from the largest pulley 58, as shown in Figure 2, onto the smallest pulley 60, as shown in Figure 4. This intermediate position for obtaining the intermediate speed of the fan is not illustrated as it is thought that it will be obvious from the description. The maintenance of the belt always in proper alignment with the fan pulley and the above described means for bodily moving the motor to insure proper tension on the belt constitute an extremely important feature of the invention.

Attention is invited to the fact that this ventilator device may be mounted in an air space where there is but little room beneath the roof and in instances where an unusually small space is available it is a simple matter to saw off the pipes 13, or replace them with shorter ones, so as to reduce the over-all height of the entire mechanism, the provision of the flexible housing or skirt 22 being important in this connection as it is obvious that upon removing the strips 23 the skirt may be pulled down to accord with the reduction in height of the device, after which the strips 23 will naturally be replaced. The device is consequently quite adaptable for easy installation under even the most adverse conditions.

A feature of distinct importance is that the belt, motor and pulleys are on the exhaust side or end of the apparatus. As a consequence it can readily be visualized that the air passing through the grille 12 will flow upwardly without any obstruction whatsoever and there will consequently be practically the same density of air at the center of the fan as on the outside edges. This could not be true if the driven pulley 37 were located at the center of the device. The air, therefore, is in natural position to be sucked upwardly and kicked outwardly by the fan blades. In other words, it could be substantially practical to draw a line showing the actual travel of the air through the plenum chamber, which would be straight up around the base 26 which, not being solid but on the contrary being legged or of spider form will offer no material obstruction.

Another feature to be noted is that all of the attachments, that is to say the belt, motor, grease cups, etc. are on the outside of the apparatus where they are readily accessible and adjustable as contrasted with other known ventilators. For instance a new belt can be put on the fan without the necessity of undoing a single nut or screw and the motor itself can likewise be removed for inspection or repairs by the owner without disturbing the remainder of the apparatus.

From the foregoing description and a study of the drawings it will be seen that I have thus provided a simple and inexpensive mechanism which will be and which has been found to be extremely efficient in operation and in which

vibration and noise are prevented so that smoothness and quietness while in operation will be assured. It is believed that the construction and advantages will be readily apparent to one skilled in the art without further explanation.

While I have shown and described the preferred embodiment of the invention, it should be understood that the disclosure is merely an exemplification of the principles involved as the right is reserved to make all such changes in the details of construction as will widen the field of utility and increase the adaptability of the device provided such changes constitute no departure from the spirit of the invention or the scope of the claims hereunto appended.

Having thus described the invention, I claim:

1. A ventilating device comprising a lower frame disposable over an opening in the floor of an attic or air space, an upper frame resiliently mounted upon said lower frame, a flexible skirt connected with and bridging the space between said frames, a rotary fan assembly mounted centrally of and above said upper frame, a drive motor carried by the upper frame and located to one side thereof.

2. A ventilating apparatus comprising a base frame adapted to be mounted above an opening in the floor of an attic or the like, guide members rising from said base frame, an upper frame including a ring and angle bars secured to diametrically opposite sides thereof, socket members depending from said angle bars for telescopically receiving said guide members, an upstanding shell carried by said ring, a depending flexible skirt bridging the space between the ring and said base frame and secured to the latter, and a motor driven fan assembly mounted at the center of the ring member.

3. A ventilating apparatus comprising connected lower and upper frame members disposable over an opening in the floor of an attic or air space, a fan assembly mounted centrally of the upper frame member and rotatable about a vertical axis, a driven pulley forming part of the fan assembly, a motor carried by the upper frame and located exteriorly at the side thereof, a plurality of drive pulleys carried by the motor shaft, a belt trained about the driven pulley and adapted to be engaged about a selected one of said plurality of drive pulleys, and means for shifting the motor bodily laterally and vertically to maintain said belt horizontal regardless of which drive pulley it is trained about.

4. A ventilating apparatus comprising connected lower and upper frame members disposable over an opening in the floor of an attic or air space, a fan assembly mounted centrally of the upper frame member and rotatable about a vertical axis, a driven pulley forming part of the fan assembly, a motor carried by the upper frame and located exteriorly at the side thereof, a plurality of drive pulleys carried by the motor shaft, a belt trained about the driven pulley and adapted to be engaged about a selected one of said plurality of drive pulleys, means for simultaneously shifting the motor laterally and vertically to compensate for the difference between the diameters of the successive drive pulleys for maintaining said belt taut and horizontal, and other means for adjusting the position of the motor with respect to the upper frame to compensate for variations in belt lengths.

5. A ventilating device comprising a lower frame disposable over an opening in the floor of an attic or air space, an upper frame resil-

- ently mounted upon said lower frame in spaced relation thereto, a skirt connected with and bridging the space between both frames, a rotary fan assembly mounted centrally of and above said upper frame at the exhaust side of the device, and a drive motor for the fan assembly located at the side and entirely exteriorly of the device whereby there will be no obstruction to the passage of air through the device.
6. A ventilating device comprising a stationary lower frame, an upper frame movable relatively thereto, both of said frames being dis-
10 posable over an opening in the floor of an attic or air space, a flexible means extending be-
tween and removably secured to said frames, a fan assembly mounted centrally of and above the upper frame and rotatable about a vertical axis, said fan assembly being at the exhaust side of the device, and a drive motor connected with
15 the fan assembly and mounted at the side and entirely exteriorly of the device to be readily
20

accessible and to avoid obstruction of the flow of air through the device.

7. A domestic ventilating apparatus comprising a grille adapted to be mounted at an opening in the attic floor of a dwelling house, a shield mounted above the opening, a skirt move-
10 able with respect to and positioned between said shield and floor, means connecting said skirt and shield, impervious means connecting said skirt and floor, a fan located at the top of the shield
and projecting thereabove, a motor connected to said first named means and operatively connected to said fan, socket members carried by said first named means, legs located at the sides of the floor opening and having their upper ends
15 positioned within said socket members, and a plurality of resilient packing elements within the socket members and supported by said legs for absorbing vibration resulting from the operation of the motor.

VERNON P. WINTON.
